(57) **CLAIM**

We claim the ornamental design for an electric mop, as shown and described.

DESCRIPTION

FIG. 1 is a right, top and front perspective view of an electric mop showing my new design;

FIG. 2 is a left, bottom and rear perspective view of the electric mop of FIG. 1;

FIG. 3 is a front view of the electric mop of FIG. 1;

FIG. 4 is a rear view of the electric mop of FIG. 1;

FIG. 5 is a left side view of the electric mop of FIG. 1;

FIG. 6 is a right side view of the electric mop of FIG. 1;

FIG. 7 is a top view of the electric mop of FIG. 1;

FIG. 8 is a bottom view of the electric mop of FIG. 1;

FIG. 9 is an exploded view of the electric mop of FIG. 1; and,

FIG. 10 is an enlarged view of an encircled portion 10 of the electric mop of FIG. 9.

(Continued)

The broken lines depict portions of the electric mop in which the design is embodied that form no part of the claimed design.
